W. O. GADD

CLOTHESPIN

Filed July 5, 1922

Inventor
W. O. Gadd,

By *John Murphy Jr.*
Attorney

UNITED STATES PATENT OFFICE.

WILLIAM O. GADD, OF SAN ANTONIO, TEXAS.

CLOTHESPIN.

Application filed July 5, 1922. Serial No. 572,764.

To all whom it may concern:

Be it known that I, WILLIAM O. GADD, a citizen of the United States, residing at San Antonio, in the county of Bexar and 5 State of Texas, have invented certain new and useful Improvements in a Clothespin; and I do hereby declare the following to be a full, clear, and exact description of the invention, such as will enable others skilled 10 in the art to which it appertains to make and use the same.

The object of the invention is to provide a simple and efficient metallic clothes pin which may be permitted to remain per- 15 manently in engagement with the clothes line whether of rope or cord or of wire, which will be frictionally retained in any position to which it may be adjusted on the line, which may be readily moved from one 20 part of the line to another to accommodate the position of the articles to be suspended therefrom, and each having means for engaging a plurality of articles so that one pin may be arranged between adjacent articles 25 on the line to engage the adjacent edges thereof; and with these objects in view the invention consists in a construction, combination and relation of parts of which the preferred embodiment is shown in the accom- 30 panying drawing, wherein:

Figure 1 is a view of a clothes pin embodying the invention applied in the operative position to a line;

Figure 2 is a side view of the same re- 35 moved from the line and shown in the normal positions of the arms whereby a tension is maintained thereon to hold the terminals of the same in engaging relation with a properly stretched and taut line;

Figure 3 is a plan view of the pin.

The pin consists essentially of a central eye 10 adapted to be threaded on the line 11 for movement in any desired direction and required distance thereon, from which project in opposite directions the engaging arms 12, said eye consisting preferably, and as illustrated in the drawing, of a plurality of coils formed at an intermediate or approxi- 45 mately central portion of a single blank of

spring or resilient wire of which the terminals are looped to form the engaging arm, the extremities of the blank being provided with hooks 13 which engage the eye to hold the parts of the pins in their proper relative positions. The looped arms are provided at 55 their outer or remote ends represented by the closed portions of the loop with transversely deflected seats 14 which lie in straddling relation with the line and serve as a means of clamping a fabric with which the same are 60 engaged in proper frictional contact with the line to prevent disengagement.

In their normal positions the arms of the pin are deflected angularly from an axial line of the eye so that when the pin is applied to the line and the latter is tensioned, so as to bring the extremities of the arms into a position wherein a straight line passing therethrough will also pass through the eye, the arms are placed under tension and therefore 65 have a transverse spring bearing action against the line to firmly engage fabrics which are suspended or looped over the line.

Having thus described the invention, what I claim is:—

A clothes pin constructed from a single blank of resilient wire bent midway of its length to form a central eye consisting of a plurality of coils, arms projecting in opposite directions from said eye and having return bends to form loops having closed ends spaced from the eye, the closed ends of said loops being deflected to form line engaging seats, the arms being yieldingly held in position to have the line engaging seat bear 85 transversely upon a line extending through the eye, said arms consisting of the terminal portions of the blank with the extremities of the blank provided with hooks for engaging the coils of the eye, and said arms 90 normally occupying a position in a plane below the axial line of the eye.

In testimony whereof I affix my signature in presence of two witnesses.

WILLIAM O. GADD.

Witnesses:

J. A. PURVIS,
H. M. LANCASTER.
